UNITED STATES PATENT OFFICE

HANS C. JORDHOY, OF PLAINFIELD, NEW JERSEY, ASSIGNOR TO WOOD NEWSPAPER MACHINERY CORPORATION, OF NEW YORK, N. Y., A CORPORATION OF VIRGINIA

REVERSIBLE FOLDER

Application filed September 17, 1926, Serial No. 136,046. Renewed February 12, 1929.

This invention relates to a double folding machine for a printing press. The principal objects of the invention are to provide a construction of folder, and means for mounting and driving a fan particularly, that permits the product to be delivered and counted either to the right from the right hand folder and to the left from the left hand folder, or to the right from the left hand folder, the right hand folder being inoperative, or to the left from the right hand folder, the left hand folder being inoperative; to provide simple means by which the fan can be shifted from one position to another in each folder for accomplishing this result; to provide means for driving the fan in one direction when in one position and in the other direction when in the other position, of such a nature that no gears have to be shifted or other connections changed; to provide a delivery belt which, without any setting of the parts by the operator, will operate in either direction in accordance with the action of the fan; to provide a double box for the fan which can be opened and closed for the purpose of securing the above mentioned change; to so combine these parts with the counters that the counting mechanism will be reversed with the fan without disassembling or reassembling; to provide a simple and efficient method of counting the papers as they are delivered from either folder in either direction or from both folders in opposite directions; and to provide a frame for supporting the whole mechanism which can be shipped with the folder set up as a unit and add to the simplicity and rigidity as well as providing a permanent alignment of the elements of the frame work.

Other objects and advantages of the invention will appear hereinafter.

Reference is to be had to the accompanying drawings, in which

Fig. 1 is an end view partly diagrammatic of a pair of folding units comprising the features of this invention.

Fig. 2 is a plan of the delivery tapes and the ratchet mechanism for operating them in either direction;

Fig. 3 is an end view of one of the ratchets used for this purpose;

Fig. 4 is an end view of the right hand fan and its driving and supporting elements with the bearings open for the reversal of the fan; 55

Fig. 5 is a similar view showing the fan in position for operating in one direction;

Fig. 6 is a fragmentary view of the end of the operating lever, this figure co-operating with Fig. 5 to show this feature; 60

Fig. 7 is an end view of the same fan with the parts in the position shown in Fig. 5 but illustrating the details below the bearings;

Fig. 8 is a similar view showing the boxes 65 open as in Fig. 4 and illustrating the detachment of the counting mechanism;

Fig. 9 is an elevation of this fan unit by itself;

Fig. 10 is an end view of the same showing 70 the counter disc;

Fig. 11 is a view of the end of the folder with parts broken away;

Fig. 12 is an end view of the frame of the machine taken by itself; and 75

Fig. 13 is a side view of the same.

Fig. 1 shows in diagrammatic form a pair of separate and distinct folding units, each unit being fitted with folding and cutting cylinders 15 and 16, folding rolls 19, delivery 80 fans 32 and delivery belts 31. The fans are placed in their bearings 40 and are rotated in the direction shown by the arrows so as to deliver the papers on the belts running as shown by the respective arrows to the right 85 and to the left. When it is desired to deliver the product from the left-hand folder, for instance, to the right-hand delivery, the fan shaft is removed from the left-hand folder entirely and the fan shaft of the right-hand 90 folder is transferred together with the fan thereon, from its bearings 40 in the right-hand folder to left-hand bearings 39 in the left-hand folder. As will appear, the operation is reversed by this change and the fan delivers to the right instead of the left. 95

I have shown the invention in a form in which the folding machine is mounted on a frame 10 which consists of a single casting to take the place of the customary pair of 100

side frames and the braces and bolts that connect them together. The bottom, four legs, and top of the frame are integral with each other, all being cast in a single piece. In these parts are cast bosses which are bored to form bearings, and on the top are integrally cast a pair of half boxes 11 and 12 designed to be bored out at the top and provided with caps 13 and 14, these latter caps being the only parts shown in Figs. 12 and 13 10 that are not integrally cast in one piece.

The machine comprises the usual folding and cutting pair of cylinders 15 and 16 which are mounted on the shafts located in these two bearings 11 and 12. These cylinders are driven in the usual way and on the shaft of the folding cylinder 15 there is a gear which drives a gear 17 on a shaft 18. On the shaft 18 is a bevel gear 20 which drives a slightly inclined shaft 21 on which is a spiral gear 22. This gear drives a corresponding spiral gear 23 which meshes with another gear 24. The gears 23 and 24 are exactly of the same size and are designed for driving the spiral fan gear 25 on the fan shaft 26. As will be seen later, this fan gear will be caused to mesh with either of the gears 23 or 24 and will drive the fan in opposite directions according to whether it is located in the bearings 39 or 40.

The gear 25 meshes with a spiral gear 25^a on a shaft 28^a supported as will be described later. This shaft also has a spur pinion 28^b driving a gear 29 on a shaft 30 which operates the delivery belts 31. These features constitute the drive of the machine. The fan 32 is mounted on the shaft 26 as usual.

It will be seen that in the two units of the folder the gears 23 and 24, the folding rolls 19, and the folding cylinder 15 are centered with respect to each other; that is, a line drawn in this case vertically from the center of the folding cylinder through the nip of the rolls 19 and through the points of contact of the pitch diameters of the gears 23 and 24 will be a straight line. This line also passes through the center of the gear 25^a and the shaft on which it is mounted. The fan shaft 26 is not on this center line.

On the shaft 30 is pivoted a frame 35 comprising levers at the two ends of the machine. This frame carries the shaft 28^a and it can swing from the position shown in Figs. 4 and 8 to that shown in Figs. 5 and 7. In its open or lower position the frame 35 comes down so that a surface on the bottom at each end rests on a cross rod 37. A cross rod 33 resting on bosses 34 cast on the frame at both ends is held in position by bolts 36.

This frame is provided at its top with a pair of supports 38 in which are mounted the two half-bearings 39 and 40 for the fan shaft 26. Across the frame 10 is bolted a plate 41 which carries thereon a pair of fixed half-bearings

42 which co-operate with the movable half-bearings when the frame 35 is elevated to complete them and hold the fan shaft in either pair of bearings. On the bearings 42 are guide pins 43 which enter holes in the supports 38 and guide them so as to move only in a vertical direction although they are pivoted on bolts or studs 44 projecting into slots 45 in the levers 35 and capable of being tightened to hold the frame 35 in adjusted position. This construction allows for the pivotal raising and lowering action of the levers and the vertical motion of the supports 38 and bearings 39 and 40. These supports have slanting rails 46 on which the fan shaft 26 can be rolled out of the units.

The frame 35 is provided with swivel bolts and thumbnuts 48 at the outer end adapted to engage a pair of spaced rests 49 on a lug 47 bolted on the frame for the purpose of holding the frame 35 up in the position shown in Figs. 5, 6 and 7. The usual paper guides 50 for the fan are shown mounted on frames 51 carried by the fan shaft. These frames have hooks 52 below, which fit under the cross rod 33 to help hold in place the frames and connected parts.

I have provided the usual counting devices, comprising a counter disc 55 carried loosely on the fan shaft 26. The disc is keyed to a gear 27 driven by a pinion 28 on the shaft 28^a. The disc has the usual notch for receiving a roll 56 which is mounted on an arm 57 fixed to a shaft 58 carried by the frames 51. On this shaft is fixed an arm 59 connected by a link 60 with an arm 61 which is fixed to a shaft 62 carried by the frames 51. On this shaft 62 is an arm 63 connected by a spring 64 with the arm 59. Fixed on the shaft 62 is a bracket 65 which carries a counter toe 66. The counter toe is elevated by the elevation of the arm 59 by the roll 56 coming out of the notch and rotating on the circumference of the disc 55. It is lowered once during each rotation of the disc in the usual manner.

The shafts 58 and 62 being mounted on the frames 51 can be removed with the fan shaft. This is indicated in Fig. 8 which shows that when the supports 38 are lowered, the hooks 52 will be brought down below and out of contact with the cross rod 33. Then the whole counting arrangement can be turned on the axis of the shaft 26 to the position shown in Fig. 8 and removed with the fan unit comprising also the guides 50.

In Figs. 2 and 3, I have shown the details of the delivery. The shafts 30 are provided with delivery pulleys 72 which operate the delivery belts 31. I have numbered all the delivery belts the same number, although there are three or more series of them. The two shafts 30 carry pulleys 72 and 73 for the belts. The shafts 30 are equipped with ratchet devices 74 which operate the pulleys 73. The ratchets on one shaft 30 are arranged as

of one hand and those on the other shaft of the other hand. When the shaft 30 at the left in Fig. 2 is rotating in the direction of the arrow the middle belts 31 will be driven in the same direction and also the whole system of belts. When the products are delivered in the opposite direction, the same functions are performed by the opposite ratchet on the other shaft 30 in the opposite direction to that illustrated. It will be obvious, therefore, that the papers can be delivered in either direction in accordance with the direction of rotation of the driving means without disassembling or reassembling any of the parts or connecting them up in any different way.

In the operation of the machine, the fan shaft 26 with the connected parts can be placed in the bearing 40 as shown in Fig. 4, 20 and the frames 35 raised as shown in Figs. 5 and 7. The bolts 48 can be fastened up by their nuts so as to hold the fan in that position. Then the gear 25 meshes with the gear 24 and the fan is driven in the direction of the arrow at the right, as shown in Fig. 1. At this time the left-hand unit can be connected up in the same way with the fan gear 25 meshing with the gear 23 of that pair, so that that fan will be rotated in the opposite direction. Then the two delivery belts will deliver in opposite directions as indicated by the arrows. All this is possible because the gear 28 on the shaft 28^a will be in mesh with the gear 27 at all times.

Now if the frame 35 is lowered as shown in Figs. 4 and 8, the fan shaft 26 can be removed entirely as stated, or it can be put into the bearings 39 and the frame 35 raised and held up in position. In this case the gears 25 and 23 on the right-hand folder will be in mesh and the centers of the gears 23, 25 and 28 will be in a straight line.

It will be seen therefore, that the printed and folded products can be delivered and counted either to the right from the right-hand folder and to the left from the left-hand folder, or to the right from the left-hand folder, the right-hand folder being inoperative, or to the left from the right-hand folder, the left-hand folder being inoperative. In other words, three different operations can be provided by lowering the frames 35 and shifting the fans from one bearing to the other, and taking out one of the fans. All this is done in this simple manner without disassembling or reassembling any of the parts of the fan or counter or even the delivery belts.

The counter mechanism is reversed as stated without taking it apart in any way, simply carrying it with the fan shaft as stated. This constitutes a very simple and efficient means for delivering and counting papers from either of the two folders in either direction or from both of them in op-

posite directions. It is particularly useful in the operation of printing presses and takes the place of the necessity for tearing down many parts and reassembling them again with the folder. The manufacture of the 79 whole frame, and the carrying of the parts to make up the whole newspaper press folder, of a single casting, instead of using two side frames fastened together with braces and bolts, is also an important feature. It is easily manufactured and shipped and when received at the other end the several elements 75 can be applied to it easily as the bearings are all in permanent alignment.

Although I have illustrated and described 80 only a single form of the invention I am aware of the fact that changes and modifications can be made therein by any person skilled in the art without departing from the scope of the invention as expressed in the 85 claims.

Therefore I do not wish to be limited to the exact form shown, but what I do claim is:

1. In a double folding device for a printing press, the combination with a pair of 90 folders, of means for delivering the product to the right from the right hand folder, and to the left from the left hand folder, and means whereby the delivery means can be changed so as to deliver from either folder 95 to the other side.

2. In a double folding device for a printing press, the combination with a pair of 100 folders, of means for delivering the product to the right from the right hand folder, and to the left from the left hand folder, said 105 delivering means on each folder being capable of detachment from the folder as a unit and replacement in a position in which it will operate in the opposite direction.

3. In a double folding device for a printing press, the combination with a pair of 110 folders, of means for delivering the product to the right from the right hand folder, and to the left from the left hand folder, supporting means on the folder frames for supporting each delivery means in two different positions, and driving means for the delivery arranged to drive the same to deliver at opposite sides in the two positions.

4. In a double folder for a printing press, the combination with the two folders and two 115 delivery fans, of supporting means for the fans arranged so that one of the fans can be removed and the other fan can be changed 120 in position to deliver under the position of the fan removed.

5. In a double folding machine for a printing press, the combination with two folders each having a fan delivery, of two sets of 125 bearings for each fan movable so as to release the fan shaft and permit it to be transferred from one set of bearings to the other.

6. In a double folding device for a printing press, the combination with a pair of 130

folders and delivery mechanisms therefor for delivering the product to the right from the right hand folder, and to the left from the left hand folder, of means whereby the delivery mechanisms can be changed to deliver from either folder to the other side when the other folder is inoperative, and a counter connected, and bodily removable with, each delivery mechanism.

7. In a double folder for a printing press, the combination with the two folders and two delivering mechanisms, of supporting means for the delivering mechanisms arranged so that one of them can be removed and the other can be changed in position to deliver under the position of the one removed, and a counter connected, and bodily removable with, each delivering mechanism.

8. In a double folding machine for a printing press, the combination with two folders each having a fan delivery, a counter and delivery belts, said delivery belts being connected with each other, of two sets of bearings for each fan movable so as to release the fan shaft and permit it to be transferred from one set of bearings to the other.

9. In a double folding device for a printing press, the combination with a pair of folders, of removable fans for delivering the product from the folders, a counter connected, and bodily removable with, each fan, and delivery belts co-operating with each fan to deliver in either direction, said fans being capable of operating in opposite directions.

10. In a double folding device for a printing press, the combination with a pair of folders and delivery fans therefor, of belts for delivering the product to the right from the right hand folder, and to the left from the left hand folder, and means whereby the belts can be operated to deliver from either folder to the other side when the other fan is inoperative, said fans being reversible.

11. In a double folding machine for a printing press, the combination with two folders each having a fan delivery, a counter and delivery belts, said delivery belts being connected with each other, of two sets of bearings for each fan movable so as to release the fan shaft and permit it to be transferred from one set of bearings to the other, and driving means for the fan shaft of each folder comprising two driving members rotatable in opposite directions at all times, the fan having a driving member connected therewith adapted to be operated by each of said driving means in opposite directions in the different positions of the fan.

12. In a double folding machine for a printing press, the combination with two folders each having a fan delivery, a counter and delivery belts, said delivery belts being connected with each other, of two sets of bearings for each fan movable so as to release

the fan shaft and permit it to be transferred from one set of bearings to the other, driving means for the fan shaft of each folder comprising two driving members rotatable in opposite directions at all times, the fan having a driving member connected therewith adapted to be operated by each of said driving means in the different positions of the fan, and means for driving the delivery belts from the fan shaft, whereby the direction of motion of the delivery belts of each unit will be reversed when the fan shaft is changed from one set of bearings to the other.

13. In a double folding machine for a printing press, the combination with two folders each having a fan delivery, of two sets of bearings for each fan movable so as to release the fan shaft and permit it to be transferred from one set of bearings to the other, and driving means for the fan shaft of each folder comprising two driving members rotatable in opposite directions at all times, the fan having a driving member connected therewith adapted to be operated by each of said driving means in opposite directions in the different positions of the fan.

14. In a double folding device for a printing press, the combination with a pair of folders, a plurality of sets of delivery tapes, driving means for the tapes, a pair of shafts having pulleys thereon for receiving the tapes, a ratchet wheel on the shaft next to the driving means for driving the tapes beyond in one direction and inoperative when driven in the opposite direction, and a second shaft having pulleys thereon for the tapes having a ratchet driven in the opposite direction, whereby the tapes can be driven in either direction without any adjustment or re-assembly of the parts.

15. In a double folding device for a printing press, the combination with a pair of folders and delivery mechanisms therefor, of means for delivering the product to the right from the right hand folder, and to the left from the left hand folder, means whereby the products can be delivered from either folder to the other side when the other folder is inoperative, a plurality of sets of delivery tapes, driving means for the tapes, a pair of shafts having pulleys thereon for receiving the tapes, a ratchet wheel on the shaft next to the driving means for driving the tapes beyond in one direction and inoperative when driven in the opposite direction, and a second shaft having pulleys thereon for the tapes having a ratchet driven in the opposite direction, whereby the tapes can be driven in either direction without any adjustment or re-assembly of the parts.

16. In a folding unit, the combination with folding mechanism, of a delivery fan and its shaft, two sets of bearings on the frame on which the fan shaft can be located to position the fan in two different places, and means

for driving the fan shaft in opposite directions in the two positions.

17. In a folding unit, the combination with folding and delivering mechanism, of a fan and its shaft constituting part of the delivering mechanism, two semi-cylindrical bearings at each end open at the top and movable toward and from their mating half bearings to a position in which the fan shaft can be moved from one to the other or removed entirely from the machine, and means for driving the fan shaft in opposite directions in the two positions.

18. In a folding unit, the combination of a fan and its shaft with a unitary construction comprising two half bearings located at a constant distance apart, a pair of half bearings registering therewith for holding the shaft, the first two named half bearings being movable away from the others to leave a space for removing the shaft from one to the other, and a pair of projections extending from the movable bearings and having inclined upper surfaces upon which the fan shaft can be removed.

19. In a folding unit, the combination of a fan and its shaft, two half bearings located at a constant distance apart, a pair of half bearings registering therewith for holding the shaft, the first two named half bearings being movable away from the others to leave a space for removing the shaft from one to the other.

20. In a folding unit, the combination of a fan and its shaft, a support having two half bearings at each end, a second set of half bearings registering therewith for holding the shaft, one set of half bearings being movable away from the other to leave a space for removing the shaft, and a counting mechanism comprising a counting disc and operating means loosely mounted on the fan shaft and removable bodily from the bearings with the fan shaft.

21. In a folding unit, the combination with a fan and its shaft, of two pairs of half bearings, two pairs of half bearings registering herewith for holding the shaft between either pair, one set of half bearings being movable away from the other to leave a space between them through which the shaft can be moved from one to the other, and a counting mechanism comprising a frame having means at the bottom for engagement with the frame of the folding machine to hold it in fixed position, said frame being mounted on the fan shaft and movable around the same for detachment from the frame and removable with the fan shaft.

22. In a folding unit for a printing press, the combination with two sets of bearings for the fan shaft, and means for driving the fan shaft in different directions when in the two positions, of a counter comprising a counting disc loosely mounted on the fan

shaft, a counter-toe connected therewith to be operated thereby, a frame for the counter mounted on, and movable with, the fan shaft, said frame having hooks extending down below the counter, a cross rod on the frame of the machine which said hooks are adapted to engage when the fan is in either of its positions, and means for lowering the fan with said frame for detaching the hooks from the cross rod to free said frame.

23. In a folding unit, the combination with a fan, of driving means therefor, two gears meshing with each other and operated constantly by the driving means so as to rotate in opposite directions, a support having two bearings at each end at a distance apart for the shaft of the fan, whereby the fan shaft can be transferred from one set of bearings to the other and its gear will mesh with one of said driving gears.

24. In a folding unit, the combination with the folding cylinders, folding rolls, a fan and delivery belts, of driving means therefor connected with the folding cylinder, two gears meshing with each other and operated constantly by the driving means so as to rotate in opposite directions, a support having two bearings at each end at a distance apart for the shaft of the fan, a shaft having a gear thereon for driving the delivery belts, the relative locations being such that the fan shaft can be transferred from one set of bearings to the other and its gear will mesh with one of said driving gears, said fan shaft having a gear thereon for driving, in both positions, the shaft which drives the delivery belt.

25. In a folding unit, the combination with the folding cylinder and a fan, of driving means connected with the folding cylinder, two gears meshing with each other and operated constantly by the driving means so as to rotate in opposite directions, a support having two sets of bearings at a distance apart for the shaft of the fan, the relative positions of the centers of each of the driving gears for the fan and the centers of the two sets of fan shaft bearings being such that the fan shaft can be transferred from one set of bearings to the other and its gear will mesh with one of said driving gears to be driven in opposite directions thereby.

26. In a folding unit, the combination with the folding rolls, of a pair of gears located adjacent thereto and meshing with each other, means for constantly driving said gears, a fan having a shaft and a gear thereon, and two bearings for the fan shaft, each located in such position that when the fan shaft is in the bearing, the gear on the fan shaft will mesh with one of said driving gears and consequently will rotate in opposite directions in the two positions.

27. In a folding unit, the combination with the folding rolls, of a pair of gears located

adjacent thereto and meshing with each other, means for constantly driving said gears, a fan having a shaft and a gear thereon, and two bearings for the fan shaft, each located in such position that when the fan shaft is in the bearing, the gear on the fan shaft will mesh with one of said driving gears and consequently will rotate in opposite directions in the two positions, a support on which said bearings are located, and a movable frame carrying said support by which the bearings can be moved into and out of operative position to support the fan shaft gear in mesh with one of its driving gears.

28. In a folding unit for a printing press, the combination with a pair of driving gears meshing together and means for driving one of them and consequently rotating the two gears in opposite directions, of a pair of stationary half bearings open at the bottom, a pair of movable half bearings registering therewith and open at the top, a fan shaft adapted to be supported in said bearings, a fan and a gear on the fan shaft, said gear being adapted to mesh with one of the first named gears in each of its two positions.

29. In a folding unit for a printing press, the combination with a pair of driving gears meshing together and means for driving one of them and consequently rotating the two gears in opposite directions, of a pair of stationary half bearings open at the bottom, a pair of movable half bearings registering therewith and open at the top, a fan shaft adapted to be supported in said bearings, a fan and a gear on the fan shaft, said gear being adapted to mesh with one of the first named gears in each of its two positions, a pair of end supports for carrying the lower half bearings, a frame pivoted at one side passing under the bearings connected to said supports for raising and lowering the bearings, means for limiting the downward motion of the frame, and means for holding the frame in its elevated position in which the movable bearings are in contact with the upper half bearings.

30. In a folding unit for a printing press, the combination with two pairs of fixed half bearings open at the bottom, of two pairs of movable half bearings open at the top and registering with the first named bearings, whereby they constitute two separate sets of complete bearings, a fan shaft adapted to be located in either set of bearings, a pivoted frame, a pair of supports for the bearings at each end of the fan shaft movably connected with said frame to move up and down with it, and means for guiding the lower half bearings to move vertically as the frame moves, whereby the fan shaft can be fixed in either set of bearings.

31. In a folding unit for a printing press, the combination of a frame pivoted to the frame of the folding unit at one side and

adapted to be fixed in elevated position at the opposite side, said frame having slots therein, a bolt passing through each slot, a pair of supports in which the bolt is located, whereby the bolts can be tightened up or loosened to hold the supports or allow them to be moved, means for guiding the supports to move vertically as the frame tilts, with a pair of half bearings carried by each support and stationary half bearings located beyond them and adapted to register with them as the frame is moved in one direction for supporting a fan shaft in either of two positions.

32. In a folding unit for a printing press, the combination with a frame extending across the frame of the folding unit at one side and adapted to be fixed in elevated position at the opposite side, and means for guiding the supports to move vertically as the frame tilts, of a pair of half bearings carried by each support and stationary half bearings located beyond them and adapted to register with them as the frame is moved in one direction for supporting a fan shaft in either of two positions, and a rod extending across the frame of the folder and having means thereon for receiving the frame in its lowermost position and limiting it.

33. In a folder unit, the combination with a frame having four legs, a bottom and top, formed in a single casting, a folding couple and shafts therefor, means on the frame for supporting the shafts of the folding couple, a fan and shaft therefor, and means supported by said frame for carrying the fan shaft in two different positions.

In testimony whereof I have hereunto affixed my signature.

HANS C. JORDHOY.
